UNITED STATES PATENT OFFICE.

CHARLES I. HUXLEY, OF ATHENS, MICHIGAN.

FENCE-POST.

SPECIFICATION forming part of Letters Patent No. 669,643, dated March 12, 1901.

Application filed July 13, 1900. Serial No. 23,535. (No model.)

To all whom it may concern:

Be it known that I, CHARLES I. HUXLEY, a citizen of the United States, residing at the village of Athens, in the county of Calhoun 5 and State of Michigan, have invented certain new and useful Improvements in Fence-Posts, of which the following is a specification.

This invention relates to improvements in fence-posts; and the improvements are particularly adapted to artificial-stone or concrete fence-posts.

The objects of my invention are, first, to provide an improved artificial-stone or concrete fence-post which shall be made of inexpensive material and at the same time be strong and durable and easy to manufacture, and, second, to provide an artificial-stone or concrete fence-post with means for securely attaching the fence to the posts quickly and 20 without the use of special tools for the purpose.

Further objects will definitely appear in the detailed description to follow.

I accomplish the objects of my invention by 25 the devices and means described in this specification.

The invention is clearly defined and pointed out in the claim.

A structure embodying the features of my 30 invention is clearly illustrated in the accompanying drawings, forming a part of this specification, in which—

Figure 1 is an elevation view of a fence-post embodying my invention, the horizontal 35 wires of the fence being shown attached thereto. Fig. 2 is a longitudinal detail sectional view of my improved fence-post, taken on line 2 2 of Fig. 1, the cores and attaching-hooks being shown in full lines. Fig. 3 is a detail 40 cross-sectional view of my improved fence-post, taken on line 3 3 of Fig. 2. Fig. 4 is a detail view of a modified form of the attaching-hooks.

In the drawings similar letters of reference 45 refer to similar parts throughout the several views.

The sectional views are taken looking in the direction of the little arrows at the ends of the section-lines.

Referring to the lettered parts of the drawings, A is the body of the post, and may be 50 of any desired composition, as Portland ce-

ment, concrete, or other stone-like material. I prefer making the same of Portland cement. It may be of any desired shape; but I prefer 55 to construct the same, as shown in the drawings, rectangular in cross-section and slightly tapering toward the top.

B are cores or binding-cables of twisted wire, around which the composition for the 60 body of the post is cast.

C is an attaching-hook for securing the wires or the complete fence to the post, and these are preferably made of wire and one end bent or clamped around one of the cables or cores, and the other projects beyond the face of the post and is left slightly open to receive one of the horizontal wires of the fence, and after the wire is placed in the hook the hook can be clamped down upon the wire, 70 if desired, and thus retain it securely in place.

In a modified structure of the attaching means shown in Fig. 4 both ends of the fastener are bent or clamped around the core, and a central loop projects beyond the surface of the post, to which fence-wires can be secured. The open hooks are preferred, as by their use the woven-wire fence may be attached to the post very rapidly, and they are also very desirable as a time-saver in attaching any fence to the post. The hooks or loops are secured to the cores before the concrete or cement composition is molded around the same and are therefore made a part of the post and securely retained in position. The 85 cores being of twisted-wire cables are very strong and cheap and light material can be used. The concrete being cast around the uneven surface of the twisted-wire cables is securely retained and does not crack or crumble away from the cores, as is likely to result when cores with a smooth surface are used, and the result is a post which can be greatly reduced in size from the ordinary concrete or artificial-stone fence-post and at the same 90 time be strong and practically indestructible.

I have described my improved artificial-stone or composition fence-post in detail in the most desirable form for accomplishing the desired end. I desire, however, to remark 100 that it is capable of considerable variation in its detail without departing from my invention. One cable only may be used for a core and the post still be strong and durable, or

more than two may be used, especially in large sizes, if for any reason it may be deemed desirable, although two cores seem to meet all requirements for the ordinary post. Twisted-iron bars might be substituted for the twisted-wire cables. Other forms of attaching hooks or loops would readily suggest themselves to one skilled in the art to which my invention pertains.

- 10 Having thus described my invention, what I claim as new, and desire to secure by Letters Patent, is—

In a fence-post, the combination of a concrete body portion A, cores B B of twisted-

wire cables with loops C surrounding one of the same, the opposite ends of which extend beyond the body portion for the attachment of fence-strands, all embedded in the cement body portion and form means to strengthen the same and avoid damage by fracture of the 20 cement body, as specified.

In witness whereof I have hereunto set my hand and seal in the presence of two witnesses.

CHARLES I. HUXLEY. [L. S.]
